UNITED STATES PATENT OFFICE.

ROY HUDDLESTON, OF DUBLIN, INDIANA, ASSIGNOR OF ONE-HALF TO
OSCAR W. GEORGE, OF DUBLIN, INDIANA.

OFFICE-DESK.

SPECIFICATION forming part of Letters Patent No. 742,118, dated October 20, 1903.

Application filed November 19, 1902. Serial No. 131,960. (No model.)

To all whom it may concern:

Be it known that I, ROY HUDDLESTON, a citizen of the United States, residing in the town of Dublin, in the county of Wayne and State of Indiana, have invented new and useful Improvements in Office-Desks; and I do hereby declare the following to be a full, clear, and exact description of the invention; such as will enable others skilled in the art to which it appertains to make and use the same.

This invention relates to desks constructed and arranged in a new and novel manner with a mechanism composed of interdependent and coöperating parts arranged to be operated by hand in order to produce certain specific objects, which will hereinafter appear.

The object of the present invention, broadly speaking, is the provision of an improved article of furniture of the class described in which is provided a rear vertically-movable section which when not needed may be depressed in order to provide a relatively large flat-top desk, a simple mechanism for operating the movable section with a minimum of time and labor, and means for slanting the forward portion of the top of the desk when desired.

Another object in view is to provide a simple, durable, and positive means for imparting to a movable section of a desk a vertical movement to close the desk or to raise and expose the front of the movable section to the operator and means for counterbalancing the weight of the movable section.

Another object is the provision of an office-desk provided with a vertically-operating section composed of a minimum of parts consistent with the various operations which it is intended to perform, which will be simple in character, compact in form and construction, easily operated and maintained, and whereby the operator will be enabled to control the mechanism, so that its work will be performed with certainty and precision and with a minimum of time and labor devoted thereto.

Another object is the provision of an article of manufacture in an office-desk of new and improved construction which can be manufactured and sold at a comparatively low price.

Other objects and advantages of my invention will appear from the following specification and from the drawings forming a part thereof.

My invention consists in an office-desk embodying certain new and useful features and details of construction and relative disposition of the parts, as hereinafter particularly set forth, illustrated in the drawings, and incorporated in the claims terminating this specification.

In detail the invention relates to office-desks, substantially as shown in the accompanying drawings, in which—

Figure 1 is a perspective view of an office-desk constructed in accordance with my invention, showing the movable section in dotted lines. Fig. 2 is a detail elevation of a portion of my desk in section. Fig. 3 is a detail in perspective of a portion of the movable section. Fig. 4 is a detail in perspective of a portion of the under side of the top of the desk. Fig. 5 is a cross-sectional view of my desk, taken on the line X X of Fig. 6. Fig. 6 is a rear elevation of my desk with the back of the desk removed to show the interior mechanism. Fig. 7 is a sectional plan view of my desk, taken on the line Y Y of Fig. 6. Fig. 8 is a detail side view of the inner ends of the supporting or counterbalance arms, and Fig. 9 is a vertical view of the same. Fig. 10 is a perspective view of one of the supporting counterbalance-standards. Fig. 11 is a perspective view of the operating-lever, and Fig. 12 is a perspective view of the curved lifting-arm.

Similar indices refer to and denote similar parts throughout the several views.

In office-desks of the class usually known as "roll-top" the sliding cover presents an uneven surface which is useless for work except to cover the top or working surface of the desk, occupies a great amount of valuable space, expensive to manufacture, and requires considerable time for its operation, while in the ordinary "flat-top" desk no provision is made for a filing-case, and in both of the above-named types of desks the tilts are usually of unnecessary length and the working surface is not adjustable to produce either a flat or slanting surface.

All of the above objections are overcome in the construction herein shown, in which a large working surface is provided; all the surfaces are level, yet with means for providing a slanting working surface, if desired; an adjustable filing-case is provided which when not in use may be entirely removed from sight, yet easily brought into view when required; no useless surfaces are produced; the tills are of a reasonable length, and no valuable space is wasted.

With the exception of the operating-lever the parts located on each side of the desk are duplicates of each other and are interchangeable, and a description of the parts on one side would consequently be a description of both.

Referring now to the drawings in detail, A represents the work surface or top of my desk.

B represents the two pedestals, which are provided with tills or storage-spaces in the usual manner, with a till b between the pedestals at the top, as shown.

C represents a partition of same height as the pedestals, which connects the pedestals in the rear of the tills. The two end outside panels of the pedestals extend rearward beyond the partition C, forming rear panels H, which may be united at their rear edges by a back D.

The pedestals B, the rear panels H, and the back D are of same height and form the framework of the desk. Extending centrally between the lower portions of the back D and the partitions C is a base-board E, which extends horizontally across the space between said parts.

F represents a vertical closure-board extending between the end panels of the desk in the rear of the partition C, the upper edge being on a level with the upper edges of the pedestals and extending down about two-thirds of the distance thereof and is permanently secured in this position.

The indice G represents the movable section of my desk of a width to neatly fit between the board F and the back D and is of a length to neatly fit between the rear panels H. The section G consists of the vertical end members gg, the horizontal top member G', uniting the end members at the top and extending over their upper ends sufficient to make its length equal to the length of the top A, and the base-shelf G'', secured between the end members gg. The lower ends of the members gg extend for some distance below the shelf G'' for the purpose of forming guides for the section G. The section G may be supplied with pigeon-holes or other form of spaces for filing purposes, as shown. When the section G is in the

position shown by the dotted lines in Fig. 1, the shelf G'' will be on a level with the top A, and when the section G is lowered to its extreme limit the top G' will be brought on a level with the top A, forming a flat-top desk, with the section G hidden from sight. In order to operate said movable section G ver-

tically from the front of the desk, I have provided a mechanism which I will now describe.

The numeral 1 represents a square shaft pivoted at each end in the hangers 2, which latter are secured to the lower edge of the board F, as shown in Fig. 6. Secured on the shaft 1 is the operating-lever 3, which extends first downward from the shaft 1 and then forward at right angles when the section G is down, or forward and then upward at right angles when the section G is up. The forward end of the lever 3 is supplied with a handhold 4, extending to the left at right angles from the lever. Secured to the face of the lever 3 are two guides 5, through which operates a plunger-rod 6, parallel to the lever 3, with a handhold 7 extending therefrom at right angles thereto and parallel to the handhold 4. The inner end of the rod 6 extends beyond the rear hanger 5, where it is provided with a square plunger 8, somewhat larger than the rod 6. Around the rod 6, between the rear hanger 5 and the plunger 8, is a resilient coil-spring 9, adapted to normally hold the plunger 8 rearward to its farthest point, as shown in Fig. 11.

The numeral 10 represents a segmental rack, on the periphery of which are notches adapted to receive the plunger 8. The rack 10 should be secured to the partition C and project forward therefrom, so that as the lever 3 is moved up and down the plunger 8 will pass over the notches thereof, and the segmental periphery of the rack 10 should be the same as that described by the plunger 8 when the lever 3 is moved from a horizontal to a vertical position.

Secured to the shaft 1 near each end thereof and extending rearward and upward therefrom (when the section G is raised) are the curved arms 11. Secured on the under side of the shelf G'' are the hangers 12, and pivotally mounted thereto and extending downward are the straight arms 13, the lower ends of which are pivotally connected to the upper ends of the curved arms 11. It will now be apparent that should the section G be up, as shown in Fig. 5, the lever 3 being horizontal, if the lever 3 be now raised to a vertical position this action will turn the shaft 1, carrying the rear end of the arm 11, downward, consequently lowering the section G, and in this position the plunger 8 will engage in the upper notch of the rack 10; also, by lowering the lever 3 to a horizontal position (shown in Fig. 5) the section G will be raised to the position shown in Fig. 5 and the plunger 8 will engage in next to the lower notch of the rack 10, which will lock the section G in that position.

The top A of the desk rests loosely on the upper ends of the pedestals of the desk, as shown, and is held in place by two offset bars 14, secured on the under side of the top A near each end of the forward part thereof, as shown in Fig. 2. The forward offset portions of said bars 14 are adapted to fit into cavities

formed opposite thereto in the upper bar at substantially the points where the indices xx are placed in Fig. 1.

Secured to each of the front edges of the end members $g g$ are the outwardly and upwardly extending lugs 15, and opposite thereto in the under side of the top A are cavities into which said lugs are adapted to enter, as shown. The position of the section G being

as shown in Fig. 5, it will now be seen that should the lever 3 be pressed down and the plunger 8 made to engage in the lower notch of the rack 10 the section G will be brought up a slight distance farther, as shown by the dotted lines in Fig. 2, by which movement the lugs 15 will raise the rear edge of the top A to the position shown by the dotted lines in Fig. 2 and by which a slightly-slanting surface is given to the top A.

In order to counterbalance the weight of the section G, so that its movements up and down may be accomplished with alacrity and ease, I have provided a mechanism which I will now describe. Secured near the lower

ends of the inner faces of the end members $g g$ are the hangers 16, in which are revolvably mounted the rollers 17, which latter are provided with a channel formed into their peripheries. 18 represents levers, the upper edges of the outer ends of which are adapted to travel in the channels in the rollers 17, and they then extend inward and downward, with their inner ends pivotally united in the center by a bolt 19, as shown in Fig. 6, and around the bolt 19 between the levers 18 is a washer 20, adapted to keep the levers 18 slightly separated. Formed into the upper edges of the levers 18 are notches 21 on alignment with each other and directly above the bolt 19. Into the

lower edges of the levers 18, near their inner ends, are a plurality of notches t , u , and v , substantially of the form and in the positions shown. Secured to and rising from the base-board E at points directly below the notches u are the standards 22, with notches 23 extending into the upper ends thereof of a width sufficient to receive the levers 18, which are placed therein, so that the notches 23 will engage in the notches u , as shown in Fig. 6. In the center of the base-board E, directly under the

bolt 19, is secured vertically a resilient coil-spring 24, with the upper end thereof secured in the notches 21 of the levers 18 and with its tension pulling downward thereon sufficient to nearly raise the section G, so that only a slight effort need be applied to the lever 3 in order to operate said section G. As the section G is moved up and down the outer ends of the levers 18 will travel in the channels of the rollers 17, thus reducing the friction thereof to a minimum.

In order to increase the power of the spring 24, the standards 22 may be sprung apart to engage in the notches t , or to reduce the power of said spring the standards may be sprung toward each other to engage in the notches v .

To further reduce the friction of the sec-

tion G when being raised or lowered, I provide grooves 25, which extend vertically in the center outer surfaces of the members $g g$, 70 and opposite thereto are rollers 26, mounted on axles secured to the inner faces of the rear panels H in such a manner that the peripheries of said rollers 26 may contact with the sides of the grooves 25, substantially as shown 75 in Fig. 7.

My invention is perfectly adapted to accomplish the results for which it is intended, and it is evident that changes in and modifications of the specific construction herein 80 shown and described may be made and that analogous parts may be used to accomplish the same results without departing from the spirit of my invention or sacrificing any of its many advantages, and the specific construction of the various details of my mechanism in which novel features are embodied 85 may be variously changed without altering the essential principles which are claimed as new.

The terms "upward," "downward," "front," "rear," and other similar terms are used for convenience of description, and it is not intended by their use to limit the arrangement of the several parts to the specific positions indicated; but they may be variously changed and modified to suit the various requirements of different types of desks.

I wish it to be distinctly understood that I do not dedicate any part of my invention to 100 the public and that I wish adequate and just protection for every feature of my invention and the various parts herein shown and described that are new and useful and which involve invention.

From the foregoing description, taken in connection with the accompanying drawings, the operation of my invention will be readily understood and its many advantages be fully appreciated, and I will simply state that the 110 device, by reason of its simplicity, lightness, attractiveness, increased capacity and usefulness, and ease and efficiency of operation, will prove a useful and practical invention.

Having now fully shown and described my 115 invention and the best mode for its construction to me known at this time, what I claim as new, and desire to secure by Letters Patent of the United States, is—

1. In a pedestal flat-top desk the combination, of a movable section mounted in the rear of the pedestals adapted to be moved vertically, a closure-board E in the rear of the partition C and parallel therewith, a shaft 1 mounted to the lower edge of the closure-board, arms 11 extending back and up from near each end of said shaft, arms 13 pivoted to and extending up from the rear ends of the arms 11, hangers 12 secured to the under side of the horizontal base of the movable 120 section to which the upper ends of said arms 13 are pivotally connected, an L-shaped lever 3 connected to the shaft 1 and projecting through the partition C, and means for lock-

ing said lever in various positions, all substantially as shown and described.

2. In an office-desk, the combination with a rearward vertically-movable filing-section 5 mounted behind the pedestals, of a counter-balancing mechanism located below the movable section and connected thereto, consisting of the hangers 16 secured to the inner faces of the lower ends of the end members 10 *g g* with rollers 17 mounted in said hangers, a pair of downwardly and inwardly projecting levers 18 contacting at their outer ends with the undersides of said rollers and united at their inner ends by a bolt 19, said levers 15 18 having notches formed in their undersides, the standards 22 secured to the base E with notches 23 in their upper ends adapted to engage in said notches in the levers 18, the coil-spring 24 secured to the base E and engaging the inner ends of the levers 18, and the washer 20 separating the inner ends of the levers 18, all substantially as described.

3. In an office-desk, a movable section mounted in the rear of the pedestals of the

desk and provided with a base-shelf above 25 the lower ends of its end members, a closure-board extending between the rear of the pedestals and the movable section, the normally flat top A of the desk resting on the top of the pedestals, the said top having cavities formed 30 in its under side near its rear edge, lugs with upwardly - projecting points secured to the front edges of the movable section slightly below its base-shelf, means for raising and lowering the movable section and the rear 35 edge of the top A from between the pedestals and a counterbalancing mechanism located below the movable section and adapted to operate thereon, all substantially as shown and described.

In testimony whereof I have hereunto signed my name to this specification in the presence of two subscribing witnesses.

ROY HUDDLESTON.
